F.M. Andres,
BY *Geo. P. Kinnel* ATTORNEY.

UNITED STATES PATENT OFFICE

FRANK M. ANDRES, OF GARRETT, INDIANA

WINDOW VENTILATOR

Application filed October 1, 1928. Serial No. 309,507.

This invention relates to a window ventilator and has for its primary object to provide, in a manner as hereinafter set forth, a device for use in connection with a window whereby fresh air may be admitted to a room without direct draft, thereby protecting the health of any one occupying the room and permitting the use of a desk or the like next to the window without danger of disturbance 10 of the papers thereon.

A further object of the invention is to provide a device for the purpose aforesaid including as parts thereof, means for protecting the window sill from rain and snow, 15 and means for preventing dirt, dust, snow and rain from flowing into the room, thereby protecting the floor coverings and furnishings within the room.

A further object of the invention is to 20 provide a device as aforesaid provided at its top with a fender for deflecting dust, snow and the like and for preventing the same from entering the room at the top of the device.

25 A further object of the invention is to provide a device for the purpose aforesaid which will maintain itself in position without the aid of nails, screws and the like, and which will not interfere with the operation of the window.

With the foregoing and other objects in view the invention consists of the novel construction, combination and arrangement of parts as hereinafter more particularly de-

35 scribed and illustrated in the accompanying drawings, wherein for the purpose of illustration is shown an embodiment of my invention, but it is to be understood that changes, variations and modifications may be resorted 40 to which fall within the scope of the invention as claimed.

In the accompanying drawings in which like numerals are employed to designate like parts throughout the same,

45 Figure 1 is a fragmentary elevation of the window frame showing an embodiment of my invention in association therewith.

Figure 2 is a vertical, transverse section 50 therethrough.

Figure 3 is a section taken on line 3—3 of Figure 2.

Figure 4 is a section taken on line 4—4 of Figure 2.

Referring to the drawings in detail, the 55 numeral 1 designates the side of a window frame and 2 and 3 respectively designate the inner and outer sills therefor. The frame sides 1 are provided with the usual vertical strips 4 and 5, between which a window 6 60 is slidably mounted.

Seated on the inner sill 2 is a base member 7, which is formed with a downturned flange 8 bearing against the outer face of the sill 2 and which is further formed with an angularly disposed portion 9 extending inwardly and upwardly for a relatively short distance into the room. The portion 9 is bent outwardly upon itself as at 10, and then returned as at 11, in spaced relation to the 70 portion 10, and forming between the portions 11 and 10 a channel 12.

Disposed at either side of the window frame is an end member 13, the lower edge 14 of which is formed with an inturned flange 75 15 for seating on the base member 7 and the rearward edge 16 of which is formed with an outturned flange 17 which bears against the rear face of the strip 5. The upper edge 18 of the end member 13 is materially 80 longer than the lower edge 14, whereby the forward edge 19 is inclined inwardly from bottom to top.

The forward edge 19 is formed with an in-turned flange 20 which has a portion 21 there-of bent upon itself and returned as indicated at 22 in spaced relation to the portion 21 thereby providing a channel 23. The flange 20 is of greater length than the portions 21 and 22 and projects beyond the ends of said portions. Likewise the base member 7 is of greater length than its angularly disposed portion 9 and projects outwardly from either end of said angularly disposed portion. Reference to Figure 3 will disclose a slight space between the horizontal plane of the upper edge of the portion 11 and the lower edge of the portion 22 as well as a similar space between the vertical plane of the inner edge of 100

the portion 22 and the outer end of the portion 11.

Carried by the base member 7 and end members 13 is an impervious plate 24, preferably of glass, which has the lower marginal portion 25 thereof seated within the channel 12 and which has the side marginal portion 26 thereof seated in the channels 23. The lower corners of the plate 24 project outwardly beyond the portions 11 and downwardly below the portions 22 as indicated at 27 in Figure 3.

Mounted at the upper, inner corners of the end members 13 is a top member 28 which is of substantially the same length as the difference between the end members 13 and has its ends overlying the forward faces of the members 20 at the upper ends of the latter. The member 28 is disposed at the same angle of inclination as the plate 24 and is formed with a portion 29 thereof bent upon itself and returned, as indicated at 30, in spaced relation to the portion 29, thereby forming a channel 31. When the top member 28 is in position, the channel 31 provides a seat for the top marginal portion 32 of the plate 24.

The member 28 terminates at its upper edge in a rearwardly or outwardly directed shield or fender 33 which curves in a returned arc as indicated at 34 and terminates with its free edge 35 adjacent the portion 30. The top member 28 is of greater length than the rearwardly extending portion 33 and extends from either end of the latter.

When the plate 24 is seated in the channels 12, 23 and 31, the side walls of the channels firmly grip the marginal portions 25, 26 and 32 of the plate on both sides of the latter and maintain the plate in position whereby the outer ends of the portion 9 of the base member 7 and also the outer ends of the portion 30 of the top member 28 are pressed against the outer faces of the flanges 20 at the upper and lower ends of the latter. In this manner the base member, end members, top member and plate are held against relative displacement and an outward pressure is exerted on the end members to grip the sides of the window frame. The flange 8 on the base member 7 holds the base member in position and also protects the finish of the sill 2 from the weather. The inclined portion 9 of the base member 7, together with the portions 10 and 11 prevents rain, dust, and the like from entering the room at the bottom of the plate 24 and the fender or shield 33 prevents the entrance of such elements into the room at the top of the plate 24.

It is thought that the many advantages of a window ventilator in accordance with this invention will be apparent and although the preferred embodiment is as illustrated and described, yet it is to be understood that various changes may be made in the details

of construction without departing from the spirit of the invention or the scope of the appended claims.

What I claim is:

1. A window ventilator comprising, a base member having an angularly disposed part formed with a channel, a pair of end members, each having at its forward edge a flange formed with a channel, said angularly disposed part having its end portions overlapping said flanges, and a plate having marginal portions thereof disposed within said channels and coacting with the walls thereof to force said overlapping portions into frictional engagement with said flanges for maintaining said base and end members in assembled relation. 70

2. A window ventilator comprising, a base member having an angularly disposed part formed with a channel, a pair of end members, each having at its forward edge a flange formed with a channel, a top member formed with a channel, said top member and angularly disposed part having their end portions overlapping said flanges, and a plate having its marginal portion disposed within said channels and coacting with the walls thereof to force said overlapping portions into frictional engagement with said flanges for maintaining said base, top and end members in assembled relation. 75 80

3. A window ventilator comprising, a base member for seating on a window sill and having an angularly disposed part formed with a channel, a pair of end members adapted to bear against the inner faces of opposite sides of a window frame and each having at its forward edge a flange formed with a channel, said angularly disposed part having its end portions overlapping said flanges, vertically disposed flanges formed at the rear edges of said end members for wedging between the window sash and frame to maintain the ventilator in position, and a plate having marginal portions thereof disposed within said channels and coacting with the walls thereof to force said overlapping portions in frictional engagement with said flanges and to exert an outward pressure on said end members for maintaining said base and end members in assembled relation and for maintaining said vertically disposed flanges in wedging position with respect to the window sash and frame. 90 95 100

4. A window ventilator comprising, a base member for seating on a window sill and having an angularly disposed part formed with a channel, a pair of end members adapted to bear against the inner faces of opposite sides of a window frame and each having at its forward edge a flange formed with a channel, a top member formed with a channel, said top member and angularly disposed part having their end portions overlapping said flanges, vertically disposed flanges at the rear 110 115 120 125 130

edges of said end members for wedging between the window sash and frame to maintain the ventilator in position, and a plate having its marginal portions disposed within 5 said channels and coacting with the walls thereof to force said overlapping portions into frictional engagement with the flanges at the forward edges of the end members for maintaining said base, top and end members in assembled relation and for maintaining 10 said vertically disposed flanges in wedging position with respect to the window sash and frame.

In testimony whereof, I affix my signature 15 hereto.

FRANK M. ANDRES.
